UNITED STATES PATENT OFFICE.

BENJAMIN S. PURKEY, OF TACOMA, WASHINGTON.

INSULATOR.

1,251,416.

Specification of Letters Patent. Patented Dec. 25, 1917.

Application filed May 4, 1914. Serial No. 836,235.

To all whom it may concern:

Be it known that I, BENJAMIN S. PURKEY, a citizen of the United States, residing at Tacoma, in the county of Pierce and State 5 of Washington, have invented certain new and useful Improvements in Insulators; and I do hereby declare the following to be a full, clear, and exact description of the invention, such as will enable others skilled 10 in the art to which it appertains to make and use the same.

This invention relates to insulators and has for its object to provide an insulator with improved means for retaining an insulated wire in position relative to such insulator.

A further object of the invention is to provide improved means for retaining the wire in position in the insulator without 20 the use of latches, ties or other fastening means.

With these and other objects in view the invention comprises certain novel constructions, combinations and arrangement of 25 parts as will be hereinafter more fully described and claimed.

In the drawings:

Figure 1 is a view of the insulator in side elevation.

30 Fig. 2 is a view of the insulator in section taken on line 2—2 of Fig. 1.

Fig. 3 is a sectional view taken on line 3—3 of Figs. 1 and 2.

Fig. 4 is a top plan view of the insulator.

35 Like characters of reference designate corresponding parts throughout the several views.

The improved insulator which forms the subject matter of this application is provided with a body 10 of any approved formation with any usual or ordinary means 40 for attaching to any usual or ordinary support not here shown and forming no part of the present invention. As shown at Figs.

45 1 and 2 a head 11 is provided although it is to be understood that the external configuration, shape or form of the insulator is also wholly non-essential to the present invention.

50 Extending diametrically across the top of the insulator is a slit 12 extending as a plane a short distance downwardly into the insulator structure and then rotating spirally on the axis of the insulator, such spiral 55 rotation being indicated at 13 in Figs. 1 and 2. The rotation of the slit-forming line

upon the axis of the insulator is such that when the wire is inserted in the slit and turned to follow the formation of the slit it stands at an angle to the slit as indicated 60 at Figs. 3 and 4, the wire being indicated at 14.

The present insulator is intended for use in connection with an insulated wire and means is provided for holding the wire 65 against longitudinal movement relative to the insulator by employing means for gripping the insulation. The means employed are ribs 15 and 16 which are formed respectively in the lower and upper walls of the 70 spiral slot as indicated at Figs. 1, 2 and 3 and preferably coinciding with lines concentric to the axis of the insulator so that as the insulated wire is forced downwardly and turned to follow the spiral slot the ribs 75 15 and 16 are pressed into the material of the insulation, thereby gripping the insulation at four points as indicated at Fig. 2 and preventing longitudinal movement of the wire. The wedging or gripping action 80 of the ribs 15 and 16 upon the insulating material of the wire also serves to prevent return movement of the wire upwardly in the slot and to thereby disengage the wire from the insulator serving not only to prevent 85 longitudinal movement of the wire but also to prevent disengaging movement of the wire from the slot.

It will be seen from the above that after the wire 14 has been inserted in the groove 90 of the insulator and securely gripped between the opposed convergently spaced gripping ridges 15 and 16 that the wire cannot be drawn diametrically across the insulator, whether the wire is taut or is 95 slack, unless there is a relative angular movement between the insulator and the wire so as to effectually disengage the latter from the wider and spaced ends of the gripping ridges.

I claim:

1. An insulator having a diametrical and spiral wire receiving slot forming a seat at its inner end in which the wire lies in a straight or undeflected position diametri- 105 cally across the insulator, and opposed, convergently spaced, gripping ridges, concentric with the axis of the insulator, on the upper and lower groove surfaces adapted to transversely bite into the insulation on an 110 inserted wire to prevent axial movement thereof whether it is tight or slack,

2. An insulator having a diametrical and spiral wire receiving slot forming a seat at its inner end in which the wire lies in a straight or undeflected position diametrical across the insulator, and pairs of opposed, convergently spaced, gripping ridges concentric with the axis of the insulator on the upper and lower groove surfaces adapted to transversely bite into the insulation

on an inserted wire to prevent axial movement thereof whether it is tight or slack. 13

In testimony whereof I affix my signature in presence of two witnesses.

BENJAMIN S. PURKEY.
